UNITED STATES PATENT OFFICE.

ROBERT M. MACINTOSH, OF BOSTON, MASSACHUSETTS.

MACHINE FOR TWISTING FIBER IN HANKS.

SPECIFICATION forming part of Letters Patent No. 405,741, dated June 25, 1889.

Application filed September 7, 1888, Serial No. 284,794. (No model.)

To all whom it may concern:

Be it known that I, ROBERT M. MACINTOSH, of Boston, county of Suffolk, State of Massachusetts, have invented an Improvement in 5 Machines for Twisting Fiber in Hanks, of which the following description, in connection with the accompanying drawings, is a specification, like letters on the drawings representing like parts.

10 This invention has for its object to provide a machine for twisting fiber in the hank to soften the same and render it smoother and more elastic, and at the same time increase its tensile strength, my improved machine 15 being especially adapted for treating linen fiber for sewing-machines, more particularly of that class in which the thread is waxed to strengthen it.

Prior to my invention linen thread in hanks 20 has been treated by hand to soften it, the said hanks being twisted so as to contract the threads. By many repeated experiments I have ascertained that linen thread can be twisted a given or predetermined number of 25 times and have its strength increased; but if twisted more than the said predetermined number the thread deteriorates in strength. When treated by hand, a uniformity of work by different operators, and even by the same 30 operator, cannot be obtained, and therefore it is substantially impossible to obtain linen threads having a uniform strength and finish.

It is the object of this invention to provide a machine by which the same or predetermined 35 number of twists may be given to each hank of thread, whereby the increase in strength of the threads is uniform, and a smoother, more elastic, and stronger thread is obtained.

40 My invention therefore consists, essentially, in a machine for twisting fiber in hanks, of two heads, and bobbins carried by them, and about which the hank is placed, one of the said heads being movable with relation to the other, combined with a main shaft, 45 gears to operate said bobbins, and a clutch mechanism to produce opposite rotations of the said shaft, and with a controlling mechanism, substantially as will be described, 50 connected to and operating the clutch mechanism to control or govern the direction and

duration of rotation of the said main shaft, and means, substantially as will be described, to produce longitudinal movement of the hank, substantially as will be described. 55

Other features of my invention will be pointed out in the claims at the end of this specification.

Figure 1 is a side elevation, partially broken out, of a machine embodying my invention, 60 the table and part of the stationary head supported thereby being broken out; Fig. 2, an end elevation, partially broken out, of the machine shown in Fig. 1, looking toward the right; Fig. 3, an elevation of the movable 65 head, looking in the direction of arrow 20, Fig. 1; Fig. 4, a section and elevation of the front portion of the machine to more clearly show the automatic stop-motion, the section being taken on line $x-x$, Fig. 5; Fig. 5, a side 70 elevation, partially broken out, of the portion of the machine shown in Fig. 4; Fig. 6, a similar view to that shown in Fig. 4, with the automatic stop-motion in operative position; Fig. 7, a side elevation of the rear portion of 75 a modified form of machine; Fig. 8, a detail to be referred to, and Fig. 9 details of the mechanism for producing rotation of the bobbins carried by the movable head.

The frame A of the machine (herein shown 80 as solid and which in practice is supported upon suitable legs not shown) sustains at its rear end a bracket or upright A', supporting one end of rods a, one at each side of the machine, having their other ends connected to a 85 stationary head, herein shown as a shell or box a' secured by bolts a² to the frame of the machine near its center. The rods a support a movable head b, (herein shown as a shell or hollow box similar to the shell or box a'), the 90 movable head b sliding upon the said rods, and having attached to it, as herein shown, a weight b' by cord b², passed over a sheave b³, supported by the upright b⁴, secured to the bed, the said weight acting to restore the 95 movable head b to its normal position. (Shown in Fig. 1.) The movable head b supports a shaft b⁵, having mounted upon it outside the said head a bevel-gear b⁶, in mesh with bevel-gears b⁷ b⁸, mounted on shafts or arbors b⁹ b¹⁰, 100 having bearings in arms b¹¹, secured to the head b. The shafts b⁹ b¹⁰ have mounted on

them gears $c'c'$, in mesh with gears c^2c^3 on shafts c^4c^5 , supported by arms b^{12} , secured to the head b . The shafts referred to have mounted fast on them bobbins c^6 ; each having its periphery curved or rounding, as shown in Fig. 3, for a purpose to be hereinafter described. The stationary head a' forms within it journal-bearings for the shaft b^5 , which constitutes the main shaft of the machine, it being provided, as herein shown, with suitable loose pulleys $c^{12}c^{13}$, which are revolved in opposite directions in usual manner by belts. (Not shown.) The main shaft b^5 within the head a' has mounted on it a gear a^8 , (see Fig. 2,) in mesh with gears c^7 , there being as many gears c^7 as there are bobbins carried by the movable head, the number of which, as herein shown, is four. The main shaft b^5 of the machine is rotated, as herein shown, by a clutch mechanism d , which is automatically thrown in engagement with one or the other of the loose pulleys $c^{12}c^{13}$, according to the direction with which it is desired to rotate the said shaft.

25 In practice a hank d' of fiber, preferably linen thread, has one end passed over one of the bobbins c^{10} , loosely mounted on an arm c^8 secured to or forming part of the shaft of the gear c^7 , and having its other end passed over one of the bobbins c^6 , preferably in line with the bobbin c^{10} , and the threads comprising the hank are laid over the curved periphery of the said bobbins, so that a substantially uniform number of individual threads will be superimposed upon each other, whereby when the hank is twisted undue strain will not fall upon some of the threads and not on others, but instead thereof all the threads of the hank will be subjected to substantially the same strain. Let it be supposed that the clutch d' is in engagement with the pulley c^{13} and that the main shaft is rotated in a direction to twist the bobbins. As the bobbins are twisted the head b is moved along the rods a and approaches the stationary head a' until the bobbins have been subjected to a given number of twists to acquire the desired tension or friction on the threads.

50 The main shaft b^5 , near the front end of the machine, has mounted upon it a pinion e in mesh with a gear e' mounted on a threaded rod e^2 supported in uprights e^3 . The threaded rod e^2 has fast upon it collars e^4e^5 , provided with lugs e^6 , which are adapted to engage lugs e^7 on a pinion or collar e^8 , having its inner periphery threaded to engage the threads of the rod e^2 , so that as the said rod is rotated the pinion e^8 is caused to travel back and forth between the collars e^4e^5 , for a purpose to be described. The pinion e^8 engages one or more teeth 25 (see Fig. 4) on the periphery of a hub e^{10} , fast on a shaft e^{12} mounted in uprights e^3e^{13} , the said shaft having a crank-arm or crank e^{15} , connected by the link e^{16} (see Fig. 2) to one arm of a clutch-lever e^{17} , pivoted in uprights e^{18} , and having its other arm forked to engage a groove in the clutch

70 d , said clutch being provided, as herein shown, with serrations or teeth 26, to engage corresponding teeth in the pulleys $c^{12}c^{13}$, the said pinion and collars e^4e^5 constituting a controlling and reversing mechanism for the machine. As the shaft b^5 revolves in the direction to twist the hank of thread the pinion e^8 is moved along one of the teeth of the hub e^{10} by the rotation of the threaded rod e^2 until a lug e^7 engages a lug e^6 on the collar e^5 . When the lug e^6 on the collar e^5 strikes the lug e^7 on the pinion, the said pinion is given a limited rotation sufficient to turn or rock 80 the hub e^{10} the distance of one tooth. As the hub e^{10} is moved the arm e^{15} , secured to its shaft, is moved, and the clutch-lever, through the link e^{16} , turned on its pivot to disengage the clutch from the pulley c^{13} and engage it 85 with the pulley c^{12} , whereby a reverse rotation of the main shaft is effected. As the main shaft is rotated in the opposite direction the gears c^7 are rotated to untwist the bobbins to the same extent that they have been twisted, 90 the weight b' moving the head b and its attached bobbins back into the normal position. (Shown in Fig. 1.) As the shaft is rotated in the reverse direction to unwind the bobbins the pinion e^8 is moved from engagement with the collar e^5 into engagement with the collar e^4 , a lug e^7 engaging a lug e^6 on the said collar e^4 . When the lug e^7 engages the lug e^6 on the collar e^4 , which by adjustment of the said collar on the shaft e is so timed as to take 100 place when the number of twists given to the hank have been taken out of the hank, the toothed hub e^{10} is restored to its normal position to engage the clutch d with the pulley c^{13} , thereby causing the main shaft to be again 105 rotated in the proper direction to twist the bobbins, the proper adjustment of the collar e^4 on the threaded rod e preventing the bobbins being twisted in the wrong or opposite direction. 110

115 In order that the hank may not be subjected to strain at the same point when it is twisted, the bobbins c^6 are rotated for substantially an instant to produce a longitudinal movement of the hank, preferably by a dog or pawl f , (see Fig. 9,) located, as herein shown, in a way or slot in the hub of the gear b^6 , the said dog or pawl being acted upon by a spring f' , which keeps it in engagement with the shaft, which, as herein shown, is cut away, as at f^2 , to form a tooth, which is engaged by the said dog or pawl when the shaft commences its rotation in a direction to twist the bobbins. The gear b^6 is thus rotated by the engagement of the dog or pawl f with 120 the tooth on the shaft, the rotation of the said gear through the gears above referred to producing rotation of the bobbins c^6 , and consequently longitudinal movement of the bobbins. The tooth f^2 on the shaft is made of such 125 length that it will be in engagement with the dog or pawl only at the beginning of the forward movement of the movable head. 130

Instead of the pawl f and tooth or notch f^2

on the shaft, I may employ a toothed hub f^5 , (see Figs. 7 and 8,) which engages the toothed end of the hub of the gear b^6 , the hub of the said gear being extended through the movable head.

It will be noticed that the rotation of the shaft is controlled by the pinion e^8 and collars $e^4 e^5$, and that the same number of twists given to the hank by the rotation of the shaft in one direction is taken out by the rotation of the shaft in the opposite direction, so that the bobbins c^6 are rotated to move the hank longitudinally when the said hank is slack or free from twists.

15 In order that the hanks may not be twisted more than a predetermined number of times, I have provided an automatic stop-motion, by which the clutch is disengaged from the pulleys and made to occupy an intermediate position. (Shown in Fig. 1.)

The automatic stop-motion consists, as herein shown, of a stud or projection g on the link e^{16} , which is engaged by a lug or projection g' on a pattern-chain g^2 , (see Fig. 4,) passed about a sprocket-wheel g^5 , having secured to it a ratchet-wheel g^6 , which is engaged by a pawl g^7 , secured to the crank e^{15} , so that as the clutch is moved from one to the other pulley the ratchet-wheel and pulley are turned one tooth—that is, a tooth for each twist of the hank. When the hank has received the desired or predetermined number of twists, the lug g' on the pattern-chain will engage the stud g on the link e^{16} and hold the clutch out 35 of engagement with the loose pulleys.

It is evident that the pattern-chain may be changed to produce any desired number of twists.

I prefer to employ loose pulleys on the main shaft; but it is evident that the said shaft may be rotated in opposite directions by suitable gearing.

The movable head is restored to its normal position, as herein shown, by a weight; and 45 while I prefer to employ a weight, I do not desire to limit myself to this construction, as a spring may be employed for the same purpose.

I claim—

50 1. In a machine for twisting fiber in hanks, the combination, with a stationary head and a bobbin carried thereby and about which one end of a hank is placed, of a horizontally-movable head and a bobbin carried by it and about which the other end of the hank is placed, gears to produce rotation of said bobbins, a main shaft, a clutch mechanism to operate it, a pulley adapted to be engaged by said clutch mechanism to produce rotation 55 of the main shaft in one direction to twist the hank, a second pulley on the main shaft to be engaged by the clutch mechanism to rotate the main shaft in the opposite direction to untwist the hank, and means, substantially as described, to withdraw the movable head from the stationary head as the

hank is being untwisted, substantially as set forth.

2. In a machine for twisting fiber in hanks, a stationary head and a bobbin carried thereby and about which one end of a hank is placed, combined with a movable head and a bobbin carried by it and about which the other end of the hank is placed, a main shaft provided with pulleys, gears to produce rotation of said bobbins, a clutch mechanism to engage said pulleys, and a reversing mechanism connected to said clutch mechanism, and consisting of a threaded rod e^2 , collars fixed thereon and provided with lugs e^6 , and a pinion or collar e^8 , traveling on said rod, and provided with lugs to engage the lugs on the said collars to automatically engage said clutch with one pulley to twist the hank a predetermined number of times, and with the other pulley to untwist the hank, and with means, substantially as described, to withdraw the movable head from the stationary head as the hank is being untwisted, substantially as described.

3. In a machine for twisting fiber in hanks, the combination, with a stationary head and a bobbin carried thereby and about which one end of a hank is placed, of a movable head and a bobbin carried by it and about which the other end of the hank is placed, gears to produce rotation of the said bobbins, a main shaft provided with pulleys, a clutch mechanism to engage said pulleys, and a reversing mechanism connected to said clutch mechanism and adapted to engage said clutch with one pulley to twist the hank and with the other pulley to untwist the hank, and with means, substantially as described, to withdraw the movable head from the stationary head as the hank is being untwisted, and a stopping device actuated by the reversing mechanism to center the said clutch mechanism, and thereby automatically stop the machine when the hank has been twisted a predetermined number of times, substantially as described.

4. In a machine for twisting fiber in hanks, a stationary head, a main shaft provided with a gear, a bobbin about which one end of the hank is placed, and a gear to rotate said bobbin, combined with a movable head through which the main shaft is extended, a gear mounted on the main shaft and carried by the movable head, and a bobbin carried by the movable head and provided with a gear in mesh with the gear on the main shaft, pulleys on the main shaft, and a clutch mechanism to engage said pulleys to produce opposite rotation of the main shaft, and means, substantially as described, to produce rotation of the gears carried by the movable head to move the hank longitudinally, substantially as described.

5. In a machine for twisting fiber in hanks, two heads and bobbins carried by them and about which the hank is placed, one of the

said heads being movable with relation to the other, and gears to produce rotation of the bobbins, as described, combined with a main shaft and a clutch mechanism to produce opposite rotations of the said shaft, and with a controlling mechanism, substantially as described, driven by the main shaft and connected to and operating the clutch mechanism to control or govern the direction and duration of rotation of the said main shaft, the said controlling mechanism automatically operating the said clutch mechanism to produce rotation of the main shaft in one direction to give to the hank a predetermined number

of twists, and to thereafter rotate the said shaft in the opposite direction to untwist the hanks the same or predetermined number of times, and means, substantially as described, to produce longitudinal movement of the hank when slack or untwisted, substantially as and for the purpose specified.

In testimony whereof I have signed my name to this specification in the presence of two subscribing witnesses.

ROBERT M. MACINTOSH.
